UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

CONNECTION MECHANISM.

Application filed May 19, 1924. Serial No. 714,526.

To all whom it may concern:

Be it known that I, RICHARD LESTER WILCOX, a citizen of the United States, residing at Waterbury, in the county of New Haven and State of Connecticut, have invented certain new and useful Improvements in Connection Mechanisms, of which the following is a specification, reference being had therein to the accompanying drawings.

10 This invention relates to a new and improved connection mechanism, of the type designed to connect a power member and an operated member, that will yield when subjected to an undue or unusual strain so 15 that one of such members may continue its movements without transmitting motion to the other member.

Among the aims and objects of this invention may be recited the provision of a 20 device of the character mentioned that will form a rigid connection under normal conditions which will become inoperative under abnormal conditions, with mechanism having a fragile element, that is compact, the 25 number of parts few, the construction simple, and the possibility of wear or lost motion reduced to the absolute minimum.

The details and arrangement of parts of this invention will be apparent from an inspection of the accompanying drawings in 30 connection with the description hereinafter contained and wherein a preferred embodiment of my invention is disclosed for the purpose of imparting an understanding of 35 the same.

In the drawings:

Figure 1 is a plan view of my improved connection mechanism showing associated therewith a fragmentary portion of a machine to which it is applied;

Figure 2 is a fragmentary side elevation thereof, the parts in section being taken generally upon line 2-2 of Figure 1;

Figure 3 is a fragmentary sectional elevation of a portion of the mechanism taken generally upon line 3-3 of Figure 2;

Figure 4 is a detail plan view of the intermediate block;

Figure 5 is a detail perspective view of 50 the filler block; and

Figures 6, 7 and 8 are fragmentary elevations similar to Figure 2 illustrating modified forms of the invention.

For the purpose of illustration only, I

have shown my improved device as associated with the mechanism for operating the plunger of a heading machine of the type substantially as shown in the patent to R. L. Wilcox, No. 1,104,090, dated July 21, 1914. As the device is equally applicable to other forms of mechanism, I desire it to be understood that by such illustration it is not intended that this mechanism should be limited to such use.

In the drawing, 10 designates the body of a heading machine, 11 a plunger that has a reciprocatory movement therein, 12 a rock lever, journaled in the body member upon a stud 13, and carrying a cam roll 14 which rides upon the face of the cam 15, from which motion is imparted to the rock lever.

The above mentioned parts are well known in the art and therefore will not be further described herein.

My invention consists in the means for 75 connecting the rock lever 12, with the plunger 11, whereby a reciprocatory movement is transmitted to the plunger.

A preferred form of this connecting mechanism consists of the intermediate 80 block 16, pivotally connected with the plunger 11 by the pin 17 held against rotation by a screw 18. In the block 16 is an opening 19 that extends through from one side to the other with a second opening 20, 85 extending from the top of the block to the opening 19. Fitted within this opening 19 is the lever block 21, which is provided at its forward end with an outwardly inclined angular shelf 22, and adjusted within the 90 gate block by a screw 23, so as to hold the face 24 thereon, at the rear of the shelf 22, in alignment with the face 25 of the opening 20. The lever block 21 and rock lever 12 are hinged together by the pin 26 that is 95 held against rotation by the screw 27.

Within the opening 20 is freely movable a shearing bar 29, one corner of the lower edge of which rests upon the angular shelf 22 (Fig. 3). This bar is held against relative movement by a filler block 32 that is preferably provided with an overhanging head 33, the underside of which rests upon the top of the block 16 and thus holds it in proper position within the opening 20; and a wedge 30, adjusted vertically by means of the screw 31, threaded into the block 16.

Fastened to the lever block 21, adjacent

to the angular shelf 22 is a chute 34, the floor of which is an extension of said shelf (Fig. 3).

All of the parts are shown in the drawings in the relative positions occupied by them when operating under normal conditions, at which time the shearing bar 29 forms a rigid connection between the block 16 and lever block 21. If, however, the strain upon the plunger 11 becomes abnormal, the rock lever 12, deriving its motion from the source of power, continues to actuate the lever block 21, which is resisted by the plunger 11. Some part, therefore, must yield and this is the shearing bar 29, which breaks off upon a line substantially parallel with the top of the lever block 21 and severs the connection between the plunger 11 and rock lever 12. No part connected with the plunger 11 now receives motion from the rock lever 12, which continues its movement as before, the lever block 21 reciprocating within the block 16. Immediately upon release, in the manner described, the lower portion of the shearing bar 29 drops onto the angular shelf 22 and slides therefrom through the chute 34 and drops therefrom out of the path of any moving mechanism, thereby eliminating any possibility of becoming entangled therewith. This positive connection between the parts is again restored by moving the wedge 30 upward slightly, thus releasing the pressure against the shearing bar, which now drops by gravity until a lower corner thereof engages the angular shelf 22 as above described. The shearing bar is again locked against relative movement by adjusting the wedge 30, so that the filler block 32 will press against the face of the shearing bar as before.

This readjustment of the portion of the shearing bar requires no manual action as it merely drops of its own weight to its new position.

45 In Figures 6 and 7 are illustrated two modified forms of wedges, neither of which are designed for use with a filler block 32, but can be so used if desired. These wedges 35 and 36 are substantially the same as wedge 30, except that in both cases it is the rear instead of the front face thereof that is at an angle. A screw 37 threaded in the block 16 so as to impinge against the shearing bar 29 may be substituted for either wedge or the wedge and filler block.

Within the scope of the appended claims, alterations and modifications may be made in the details of my invention, aside from those herein suggested, and therefore I do not limit myself to the exact construction herein shown and described.

What I claim is:—

1. In a connection mechanism; companion members, one of which is slidably relatively to the other; and a shearing bar or

the like for holding the members together as a unit under normal conditions, adjustably secured to one member and projecting into the path of movement of the other member, one of the positions of the shearing bar being determined by a shelf on the latter member.

2. In a connection mechanism; companion members, one of which is slidably mounted relatively to the other; and a shearing bar or the like fixed in one member, projecting into the path of movement of the sliding member, for holding the members together as a unit under normal conditions, the arrangement of the parts being such that the relative position of said shearing bar or the like is determined by its contact with an angular shelf portion of the sliding member.

3. In a connection mechanism; companion members, one of which is movably mounted within the other; a shearing bar adjustably connected with the outer member and projecting into the path of movement of the inner member for holding said members together as a unit under normal conditions, the inner member being so formed as to provide means for limiting the inward position of the shearing bar, and provide means for guiding out of the connection mechanism that portion of the shearing bar broken off by the relative movement of the inner and outer members.

4. In a connection mechanism of the character described; an outer member having a transverse opening therethrough and a second opening at an angle thereto and connected therewith; an inner member mounted in the first of said openings; a shearing bar in the second of said openings projecting into the path of movement of said inner member, whereby said members are held together as a unit under normal conditions; and means for adjustably securing said shearing bar to said outer member.

5. In a connection mechanism of the character described; an outer member having a transverse opening therethrough and a second opening at an angle thereto and connected therewith; an inner member mounted in the first of said openings; a shearing bar in the second of said openings projecting into the path of movement of said inner member, whereby said members are held together as a unit under normal conditions; and independent mechanism adjustably connected with the outer member for securing the shearing bar in a fixed position relatively to the outer member.

6. In a connection mechanism of the character described; an outer member having a transverse opening therethrough and a second opening at an angle thereto and connected therewith; an inner member mounted in the first of said openings; a

shearing bar in the second of said openings projecting into the path of movement of said inner member, whereby said members are held together as a unit under normal conditions; and adjustable wedge means for securing said shearing bar to said outer member.

7. In a connection mechanism of the character described; an outer member having a transverse opening therethrough and a second opening at an angle thereto and connected therewith; an inner member mounted in the first of said openings; a shearing bar in the second of said openings projecting into the path of movement of said inner member, whereby said members are held together as a unit under normal conditions; means for adjustably securing said shearing bar to said outer member; and a chute fixed relatively to said inner member to convey away from the connection mechanism that portion of the shearing bar broken off by the relative movement of the outer and inner members.

25 8. In a connection mechanism; companion members, one of which in part is slidably mounted within the other, this latter member having an angular shelf which inclines downwardly to one side thereof; a shearing bar adjustably connected with the outer member and projecting into the path of movement of the inner member for holding said members together as a unit under normal conditions, the inward position of the 30 shearing bar being determined by said shelf; and a chute connected with said slideable member opposite said shelf.

9. In a connection mechanism; companion members, one of which in part is slidably mounted within the other, this latter member having an angular shelf which inclines downwardly to one side thereof; a shearing bar adjustably connected with the outer member and projecting into the path of movement of the inner member for holding said members together as a unit under normal conditions, the inward position of the shearing bar being determined by said shelf; and a chute connected with said slideable member opposite said shelf, with a part thereof projecting in front of that portion of the bar in engagement with the slideably mounted member.

10. In a connection mechanism, companion members, one of which in part is slidably mounted within the other, this latter member having an angular shelf which inclines downwardly to one side thereof; a shearing bar adjustably connected with the outer member and projecting into the path of movement of the inner member for holding said members together as a unit under normal conditions, the inward position of the shearing bar being determined by said

shelf; and a chute connected with said slideable member opposite said shelf with its floor forming an extension of the shelf.

11. In a connection mechanism; companion members, one of which in part is slidably mounted within the other, this latter member having an angular shelf which inclines downwardly to one side thereof; and a shearing bar adjustably connected with the outer member and projecting into the path of movement of the inner member for holding said members together as a unit under normal conditions, one of the corners of said bar engaging said angular shelf which forms a support therefor.

12. In a connection mechanism of the character described; an outer member having a transverse opening therethrough and a second opening at an angle thereto and connected therewith; an inner member mounted in the first of said openings; a shearing bar in the second of said openings projecting into the path of movement of said inner member, whereby said members are held together as a unit under normal conditions; and adjustable wedge means for securing said shearing bar to said outer member, comprising a block, a wedge, and means for securing the same to the outer member, whereby the latter may be moved relatively thereto.

13. In a connection mechanism of the character described: an outer member having a transverse opening therethrough and a second opening at an angle thereto and connected therewith; an inner member mounted in the first of said openings; a shearing bar in the second of said openings projecting into the path of movement of said inner member, whereby said members are held together as a unit under normal conditions; and adjustable wedge means for securing said shearing bar to said outer member, comprising a block limited in its movement in one direction, a wedge, and means for adjustably connecting the wedge to the outer member.

14. In a connection mechanism of the character described; an outer member having a transverse opening therethrough and a second opening at an angle thereto and connected therewith; an inner member mounted in the first of said openings; a shearing bar in the second of said openings projecting into the path of movement of said inner member, whereby said members are held together as a unit under normal conditions; and adjustable wedge means for securing said shearing bar to said outer member, said wedge means and sliding bar being within said second opening.

In testimony whereof, I have hereunto affixed my signature.

RICHARD LESTER WILCOX.
